UNITED STATES PATENT OFFICE.

OSCAR BERNHARD HELLSTRÖM, OF SYDNEY, NEW SOUTH WALES.

COMBINED CORNICE AND CURTAIN-HANGER.

SPECIFICATION forming part of Letters Patent No. 657,538, dated September 11, 1900.

Application filed December 12, 1899. Serial No. 740,113. (No model.)

To all whom it may concern:

Be it known that I, OSCAR BERNHARD HELLSTRÖM, a subject of the King of Sweden and Norway, and a resident of Sydney, in the 5 county of Cumberland and Colony of New South Wales, have invented a certain new and useful Combined Cornice and Curtain-Hanger, of which the following is a specification.

10. This invention has been devised for the purpose of lessening the difficulties that housewives encounter in hanging lace and other curtains.

To this end the invention comprises a cornice-frame with two articulated folding slips, 15 between which the curtain is placed, and a retaining flange or batten for retaining in the folded position the plaited slips and curtain. It further includes the construction 20 and arrangement hereinafter described, and pointed out in the claims.

The external surface of the cornice may be decorated in any suitable manner. The cornice is constructed with its top and end sides 25 hinged or articulated, so that they may be opened outward, while its back and bottom sides are left quite open. The cornice will be provided with means whereby it may be hung on the molding above the window. Attached to the rear side of the front of the 30 cornice is a pliable or articulated slip of any suitable material and of any desirable width. This slip should be of about the same length as the width of the curtain and should be so 35 constructed that it may be folded in plaits and when thus folded would lie within the limits of the half-cornice with which it is connected. A similar slip of flexible or articulated material will be laid upon the first or 40 lower slip, with the curtain between, so that when the two slips are folded together into plaits the curtain shall be gripped firmly by the two slips and hang in folds or plaits. Instead of the articulated slip being hidden 45 behind the cornice it may be inclosed within a hollow ornamental curtain-pole.

In the accompanying drawings, Figure 1 is a rear elevation of the combined cornice and curtain-hanger with the curtains fixed in position ready for hanging. Fig. 2 is an underneath plan of the appliance viewed from be-

low, but without the curtains. Fig. 3 is a view of the extreme right-hand end part of Fig. 2, but with the end open and the top thrown back into the position shown in Fig. 55 4. Fig. 4 is an end elevation of the extreme right-hand end of Fig. 1, but with the end open, as in Fig. 3, and the top raised. Fig. 5 is a detail of the articulated slips shown folded on the left-hand side of Fig. 2 and 60 illustrates the manner in which the two slips will be straightened out and opened ready to receive the upper end of a curtain. Fig. 6 is a front elevation, partly in section, showing the articulated slips inclosed in a curtain- 65 pole.

A, Fig. 2, is the lower edge of the front face of the cornice, which may be ornamented in any suitable or tasteful manner. Articulated at *a a'*, near the center of the cornice, to the rear side of the front face, are the two slips *B B'*, which are hinged or jointed at the points *b b'*, so that they may be folded into plaits. The free end of the upper slip *B* is provided with an end piece *C*, 70 which is absent from the under slip *B'*. The reason for this will hereinafter be made plain. The top *D* and ends *E E'* are hinged at *d* and *e e'*, so that they may be opened outward. They are also respectively provided with 75 hinged clips *F F' F'*, whereby they may be firmly retained in the closed position, the hinges being shown at *f f' f'*. The under side of the top *D* is provided with a retaining flange or batten *G*, which is employed to retain in position and secure the slips *B B'* when the curtain has been placed between them and folded. Within each of the ends *E E'* is a channel-piece *h h'* to receive and retain the extremities *C* of the slips *B* when 80 the whole appliance is closed up. The curtains *J J'* are shown in position and secured in Fig. 1.

The *modus operandi* is as follows: The cornice is laid face downward on a table. 95 The clips *F F' F'* are released, when the top *D* and the ends *E E'* will open outward into the positions shown at Figs. 3 and 4. The extremities *C* of the slips *B* are released from the channel-pieces *h h'*, and the slips *B B'* 100 are then opened out, as shown in Fig. 5. The curtain *J* is laid evenly between the slips

B B'. The top slip B is then laid upon the curtain and the two slips are then folded up, as shown at Fig. 2. The top D is then closed and secured by the clip F. By closing D the 5 flange or batten will be laid against the folded slips and will retain them in position. The extremities C are laid into the channel-pieces h h', and the ends E E' may then be closed and secured to the top D by means of 10 the clips F' F''. The clip F is secured to the rear side of the front face A of the cornice. The appliance may then be suspended by the eyes or rings K K above the window, said eyes being carried by the top D.

15 For convenience of illustration the cornice has been shown of double construction; but it is considered preferable that each half of the cornice should be independent of the other half, so that one curtain only might be 20 fixed and suspended at one time.

Referring now to Fig. 6, instead of the articulated slips B being secured to the cornice A they may be inclosed within a hollow cylindrical cornice-pole J². This cornice-pole 25 is constructed in two halves, divided longitudinally, the two halves being hinged together at j j'. When the pole is opened, the slips B will be released and will allow of the curtains being folded between them. When 30 the slips are folded up, the pole will be closed and retained in the closed position by means of the ornamental caps or finials L, which fit over the pole at each end. A longitudinal slot is formed in the bottom of the pole, so as 35 to allow the curtains to hang through.

It is obvious that many of the details of construction as illustrated in the drawings may be varied without in any way departing

from the main principle upon which the invention is based.

Having now described my invention, what I claim as new, and desire to secure by Letters Patent, is—

1. In combination, a cornice-frame, with two articulated folding slips, between which 45 the curtain is placed, and a retaining flange or batten for retaining in the folded position the plaited slips and curtain, as specified.

2. In combination a front plate, which is provided with a hinged top and ends, two articulated or jointed slips hinged to the rear side of the front plate and so arranged that they can be folded into plaits, means for securing the free ends of the jointed slips, means for securing and retaining in the folded position the folded slips, and means for securing all the hinged or articulated parts of the appliance firmly together as and for the purposes set forth.

3. In combination, two articulated fold- 60 ing slips, arranged opposite each other and adapted to be folded and hold the curtain between them in folds, and means for holding the slips in folded condition, substantially as described.

4. In combination, an articulated folding slip, the sections of which when folded overlie each other, and means for holding the slip in folded condition, substantially as described.

In witness whereof I have hereunto set my hand in presence of two witnesses.

OSCAR BERNHARD HELLSTRÖM.
